Primary Examiner — Dana K Weiland*Assistant Examiner* — Messina L Smith(74) *Attorney, Agent, or Firm* — Muncy, Geissler, Olds & Lowe, P.C.(57) **CLAIM**

The ornamental design for an earphone tip, as shown and described.

DESCRIPTION

FIG. 1 is a perspective view of an earphone tip showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross-sectional view thereof taken in the direction of line 8-8 in FIG. 2;

FIG. 9 is another perspective view thereof; and,

FIG. 10 is a perspective view showing the earphone tip assembled with an earphone.

The broken lines are directed to environment and are for illustrative purpose only; the broken lines form no part of the claimed design.

1 Claim, 10 Drawing Sheets(56)
